ATTORNEYS

For a device for dispensing chips such as in games of chance, or for dispensing tokens or coins, or for dispensing other articles, the invention may be applied to any article which may be held in a stack, and which may be actuated for removal.

UNITED STATES PATENT OFFICE

2,515,904

CHIP DISPENSER

Blanchard D. Smith, Atlanta, Ga., assignor to
Nelson J. Jewett, Arlington County, Va.

Application December 28, 1944, Serial No. 570,157

5 Claims. (Cl. 133—5)

1

This invention relates to devices for dispensing chips, and particularly in games wherein counters of varying denominations and colors comprise a stack for each player.

In the prior art mechanical means have been provided for ejecting partially from each stack a certain desired number of counters so that the banker might remove counted stacks from the various compartments, however, such arrangements are slow and tedious, and one object of this invention is to provide a simple mechanism for depositing in front of any or all players a complete stack of counter chips of varying denomination by a single movement of the hand. Even during the deal this action is so natural and quick that the play is hardly interrupted.

Another object of this invention is to furnish such a dispenser so simple and cheap that its cost is no more than that of an ordinary holding rack for chips. In its preferred form it would be made of two plastic parts easily molded. A single coil spring is added to these but is not an essential part.

My invention is illustrated in the accompanying drawings in which like letters refer to like parts throughout.

Figure 1 is a plan view.

Figure 2 is a vertical section taken along the line 2—2 of Figure 1 showing the chip holders expanded for delivery of chips.

Figure 3 is a detail section with one of the parts raised above the position shown in Figure 2.

Figure 4 is a detail section along the line 4—4 of Figure 1.

Figure 5 is a detail bottom plan view showing an auxiliary spring member with the parts somewhat enlarged in scale.

The chip dispenser as shown in Figure 1 comprises four compartments for chips such as a blue, red and two white stacks. Arcuate walls 10 confine loosely the stacked array, and near the bottom along a common horizontal plane are molded projecting lugs 11 and 12, which are spaced from the bottom of the container a height corresponding to the thickness of the number of chips to be dispensed at each actuation. In the normal molded position of the parts these lugs lie within the diameter of the chips and, as shown, between the rounded edges of the fifth and sixth chip as positioned in Figure 2.

To enclose the stacks of chips four pairs of arcuate walls 10 are shown, the walls of each pair merging into a rib 13, the inward edges of which ribs are free of each other and are grouped around a central space. To hold the ribs 13 in

assembly the ribs 13 are joined at their upper inner ends by a plate member 14 forming arcuate flanges over the angle between the ribs, and which merge into the upper ends of the ribs at the point of junction of the arcuate walls 10.

To receive an actuating plunger 15, a central opening 16 is formed in the plate 14. The ribs 13 are shown as formed with cam members 17, which normally stand within the central space in positions spaced apart less than the diameter of the opening 16 and less than the diameter of the plunger. To coact with the cams 17 the plunger is formed with a frusto conical cam portion 18 which normally stands in the position shown in Figure 3, with relation to the cams 17.

To enable the suspension of the device with its load of chips when the knob 19 of the plunger is grasped and lifted, the end of the plunger is shown as formed with a disk head 20 desirably rounded or beveled at the lower outer portion of its periphery. The external diameter of the head 20 is no larger than the diameter of the plunger 15 and hence will pass freely through the opening 16, for assembly of the parts, and the head 20 will separate the ribs 13 and snap to position as shown in Figure 3.

In operation, stacks of chips are placed in each space partly surrounded by the arcuate walls 10, which stacks will be supported by the lugs 11 and 12. The device carrying the chips may then be placed on the table before each person desiring chips and the plunger 15 pressed to the position of Figure 2, thus spreading the lower ends of the ribs 13 and arcuate walls 10 with distortion of the walls. When so spread the stacks of chips are released by the lugs and fall to the table. Pressure on the plunger being released the cam surfaces 17 and 20 will return the plunger to the position illustrated in Figure 3, and the lifting of the device away from the deposited chips as indicated in Figure 4 will assist the return to normal. Such return will cause the wedge shaped lugs 11 and 12 to force themselves between two chips in each stack and result in the lifting of the stacks away from the dispensed chips, when the device is lifted.

To assist the resilience of the flanges 14 in returning the ribs 13 to normally parallel position a spring may be provided. To this end a resilient rectangle of spring wire 21 formed integrally and having its ends 22 inserted in a recess 23 is shown. This spring member seats behind shoulders 24 in the ribs 13 provided as indicated clearly in Figure 2. The faces of these shoulders are desirably rounded as shown.

Formed as shown each side of the rectangle of the spring becomes an individual spring resisting outward deformation.

In operation, in flexing outwardly on ninety degree radii, the lugs 12 do not in themselves tend to release a stack but the lugs 11 in outward travel enlarge the diametral opening sufficiently that the chips may drop through to the table top as shown in Figure 2. This flexing is manually operated by the knob 19 which, upon being depressed, utilizes the tapered cam portion 18 to thrust outwardly the cams 17 integrally cast on the ribs 13. This action is accomplished naturally when the container rests on the table top in front of a player and the knob 19 is forced downwardly.

When the knob is raised to lift the chip container, then the cams 17 immediately return inwardly as shown in Figure 3 and the continued up movement of the knob is halted by the cams 17 engaging the flanged head 20. Simultaneously with the inward movement of the cams 17, the lifting lugs 11 and 12 slide in between the fifth and sixth chip from the bottom in the form shown, and further lifting brings the container clear of the five bottom chips as illustrated in Figure 4. This action is common to all compartments and twenty desired chips of varying denomination may thus be deposited in front of the requesting player. It is readily seen that the motion of lifting the container by the knob, moving it in front of a player, lowering to the table top and by continued down push on the knob dispensing of the chips is all a quick and natural movement of the hand. As the container is brought back by the banker its natural condition is with the knob up and a void space below the chips from the lugs 11 and 12 downward.

Plastics have a slight cold flow and lose their flexibility under distortion, hence the use of the spring 24 shown enlarged in Figure 5. It holds the bottom portions of the device in their inward positions and prevents the rupture of the top flange section by any accidental strain. Its square shape approaches a circle under normal stress and it is assembled by pressing the upwardly extending prongs 22 into the molded hole 23 in the base of the container, and contacts the shoulders 24 molded on the ribs 13. The knob is originally assembled by simply thrusting it into the container, after which the spring is added. The molding of the container and knob can be accomplished in a simple open and close mold.

It is readily seen that another number of compartments other than four may be designed around the central knob, without departing from the scope of my invention.

Minor changes may be made in the physical embodiments of the invention within the scope of the appended claims without departing from the spirit of the invention.

I claim:

1. In a chip dispenser, in combination: a plurality of walls standing in positions radiating from a common axis; their inner edges spaced from said axis to provide a central passage; a common frame member secured to the upper ends of said walls and formed with a central opening to said passage; the outer edges of each of said walls bifurcated and each branch thereof constituting an arcuate extension; arcuate extensions of adjacent walls at least partially en-

closing chip holding chambers; means to support a stack of chips in each chamber; and means carried in said central passage operable to spread the lower portions of said walls to release a predetermined number of chips from each stack at each operation.

5 2. In a chip dispenser, in combination: a plurality of vertical walls standing in planes radiating from a central space with parallel inner free edges; the outer edges of each wall bifurcated into arcuate walls; pairs of said arcuate walls extending toward each other to provide chip enclosing chambers; lugs projecting from said walls into said chambers at points spaced 10 from the bottom of said chambers to support stacks of chips in said chambers; resilient plate means uniting the top ends of said radiating walls and formed with a central opening to said central space; and means reciprocable in said 15 space engaging means on the inner edges of said radiating walls to cause separation of the lug carrying portions of said walls and carried lugs to release said stacks; said lugs re-entering said stacks upon release of said means to separate a predetermined number of chips from each stack.

20 3. In a chip dispenser, in combination: side walls formed to loosely guide and confine a stack of chips; constricting lugs carried by said side walls for normally choking the passage provided by said side walls at a predetermined height from its bottom; and means operable independently of the chips for causing motion of one lug-carrying portion of said walls relative to another thereof to cause separation of said lugs to permit the lowermost chips of the stack of chips to drop to the bottom of the passage.

25 4. In a chip dispenser, in combination: side walls providing a chip passage to loosely guide and confine a stack of chips; passage constricting lugs carried by said side walls at a predetermined height from the bottom of the passage, adapted to alternately support chips in the passage and allow the chips to drop therein upon distortion of said side walls, with consequent 30 separation of the lugs and means exterior of the side walls and acting independently of the chips to cause such distortion of the side walls.

35 5. In a chip dispenser, in combination: a plurality of assembled containers for stacks of chips comprising arcuate side walls providing chip passages for loosely confining and guiding said stacks; an operating knob; sets of passage constricting lugs carried by said walls at a predetermined height from the bottom of each for choking said passages; and wedge means operable by said knob for moving at least one of each set of lugs to cause separation of the lugs of each set to permit chips to pass between the same.
